CLOSURE CAP FOR GLASS CONTAINERS

George F. Chaplin, Elmwood Park, Ill., assignor to Continental Can Company, Inc., New York, N.Y., a corporation of New York

Filed Oct. 26, 1961, Ser. No. 147,926

5 Claims. (Cl. 215—40)

This invention relates, generally, to improvements and innovations in closure caps for hermetically sealing glass containers. More particularly, the invention relates to such closure caps which are of the rotatable type with an annular gasket having both top and side seal areas for establishing and maintaining a hermetic seal on a glass container in which the top surface of the rim, together with a contiguous tapered side surface, constitute the glass sealing finish.

Closure caps embodying this invention are characterized by their outstanding ability to withstand high overriding (i.e. differential) pressures in the order of 15 to 20 pounds per square inch during retorting, and their excellent resistance to shocks and impacts without the hermetic seals being broken. Structurally, they are characterized by annular gaskets each having (1) at the top a thick cushion portion for withstanding impacts and shocks as well as high overriding pressures, (2) a tapered, relatively thin side seal portion maintained under radial compression by the surrounding metal of the cap shell which is under hoop tension, and (3) an outwardly turned feather edge portion located at a substantial distance from the glass finish so as to be unaffected by the sealing forces and pressures acting on the main body portions of the gasket.

The object of the invention, generally stated, is the provision of rotatable closure caps for hermetically sealing glass containers, the caps being characterized by the formation of excellent hermetic seals which are not broken even when the sealed containers are subjected to high overriding pressures and shocks and impacts which would ordinarily result in broken seals.

An important object of the invention is the provision of closure caps of the class described for glass containers, the caps having an inwardly and upwardly stepped thin metal shell with an annular gasket disposed at the corner juncture between the top panel portion of the shell and the inner stepped portion and providing (1) a thick cushion portion for engaging the upper edge of the glass finish, (2) a downwardly tapered, elongated side seal portion for sealingly engaging an inclined sealing finish area on the glass container rim, and (3) an outwardly flared anchoring portion terminating in a feather edge on the underside of the shell shoulder portion intermediate the steps thereof.

Another important object of the invention is the provision of rotatable closure caps for glass containers of the class described wherein the main gasket seal for protecting the contents of hermetically sealed containers from the atmosphere is in the form of an elongated, thinned-out, tapered circumferential portion maintained under radial compression by the surrounding band portion of the closure cap shell which is outwardly flexed so as to be under hoop tension.

A further important object of the invention is the provision of a closure cap of the type described for glass containers wherein the annular gasket has both top and side hermetic sealing areas, and wherein the outermost portion of the gasket joins the cap shell in a feather edge which is highly resistant to dislocation and which terminates on the underside of a generally horizontal portion of the cap shell forming a shoulder intermediate the inner and outer stepped portions of the shell skirt.

Certain other objects of the invention will, in part, be obvious and will in part appear hereinafter.

For a more complete understanding of the nature and scope of the invention, reference may now be had to the following detailed description thereof taken in connection with the accompanying drawings, wherein:

FIG. 1 is a side elevational view of a glass container hermetically sealed with a closure cap which represents one embodiment of the present invention;

10 FIG. 2 is a top plan view of the closure cap shown in FIG. 1;

FIG. 3 is a bottom plan view of the closure cap shown in FIG. 1 removed from the glass container;

15 FIG. 4 is a sectional view taken on line 4—4 of FIG. 3 and on enlarged scale;

FIG. 5 is a diagrammatic layout of the thread formations on the glass container finish for cooperation with the inturned lugs on the closure cap;

20 FIG. 6 is a greatly enlarged detailed section view showing the relationship between the sealing gasket and the glass sealing finish when the cap is loosely resting on the container; and,

25 FIG. 7 is an enlarged detailed sectional view corresponding to FIG. 6 but showing the relationship between the sealing gasket and the glass finish when the closure cap is in the fully sealed condition.

In FIG. 1, a glass container 5, such as a glass baby food jar, is sealed with a closure cap 6 constituting one embodiment of the invention. This food package illustrates one of the large volume uses of the closure caps forming the subject matter of this invention. Referring to FIG. 4, the closure cap 6 consists of a cap body or shell having a top panel portion indicated generally at

30 7, a stepped depending skirt portion indicated generally at 8. Within the shell and disposed in the corner where the top panel portion 7 intersects or joins the upper and inner step portion of the skirt 8, there is an annular gasket 10. As is well understood in the art, the cap bodies or shells are stamped out from suitably coated and decorated

35 tin plate, although other materials may be used. The machinery and methods for stamping out the cap bodies or shells in large quantities are conventional and do not form a part of the present invention. Generally, the tin plate or other material is enameled or coated both

40 on the interior and exterior with known enamel or coating formulations so as to form a protective coating on the interior of the cap body of the shell and a decorative protective coating on the exterior thereof. Often the coating on the interior is different from that on the exterior.

45 Various coating or enamel formulations may be used on the interior and usually they will be selected with a view of providing good adherence with the gasket 10, or at least being compatible therewith.

50 As shown in FIGS. 3 and 4, the bottom edge of the cap skirt 8 is inwardly rolled or curled as indicated at 11 so as to provide a strong, smooth bottom edge, with the continuity of the bead 11 being interrupted by four equally spaced lug formations 12—12 which are formed

55 by suitably deforming the bead 11. After a cap shell has been stamped out from a flat sheet, the inturned bead 11 and lugs 12 are formed in known manner by high speed machinery well known in the art. The inwardly projecting lugs 12—12 have inter-locking engagement on

60 the undersides of four inclined, interrupted thread formations 13—13 on the exterior of the container neck as shown in FIG. 5. In this figure one-half or 180° of the container neck is shown laid out flat in plan view, it being understood that all together there are four of the symmetrical threads or lugs 13, each of which is inclined

65 and overlaps with another at the opposite ends in the manner shown in FIG. 5.

The present invention is primarily concerned with the particular conformation of the cap shell in the region of the corner formed in part by the top panel portion 7 and in part by the depending skirt portion 8 together with the special conformation of the gasket 10 lodged in place therein. Reference is now made to FIGS. 6 and 7 for a detailed description of these features of the closure cap 6. Adjacent the outer periphery of the top panel portion 7 and forming the outer margin thereof, the cap shell has a down-turned channel portion indicated generally at 15 in FIGS. 6 and 7 with the inner wall thereof being indicated at 16, the outer wall portion being indicated at 17, and with the flat interconnecting portion of the channel being indicated at 18. The outer wall portion 17 integrally merges with a downwardly, and outwardly tapered skirt portion 20 which at its lower end merges with a reversely curved portion of the skirt 21. The skirt portion 21 which connects with the lower end of the skirt portion 20 is both outwardly and downwardly flared and the middle of this double-curved portion 21 constitutes a shoulder intermediate the inner step portion 20 of the skirt and the outer, substantially straight or vertical, portion 22 thereof which carries the bead 11 and lugs 12.

The gasket 10 includes a main cushion portion 23 which completely fills the downward channel 15, and a downwardly and outwardly tapered elongated portion 24 which follows down along the inside of the tapered portion 20 of the cap shell. At its lower end, the gasket 10 terminates in an outwardly flared feather edge portion 25 which actually ends at approximately 26 underneath the shoulder portion of the shell. It will be seen that the upper edge of the gasket 10 terminates on the underside of the top panel portion 7 adjacent the bottom end of the channel forming wall 16, as indicated at 27.

The gasket 10 may be formed of various known rubber-like resilient gasket materials having the desired physical and chemical properties. A preferred class of materials from which the gaskets 10 may be formed are the resin compositions known in the art as "plastics." A preferred plastisol type gasket composition is described in detail in Unger and Zipper Patent No. 2,874,863. The gaskets 10 may be deposited in the cap shells by various known techniques, one being the so-called "flowed-in" technique wherein the plastisol composition is uncured, paste-like condition is squirted from one or more nozzles into the cap shells (at position 8 cap shell portion FIG. 5) which are turned upside down on a chuck rotating at high speed. Due to centrifugal force the gasket material will assume the desired contour and shape. After being thus deposited or "flowed-in" the gaskets are cured or set by a heating operation according to known procedures and using known equipment. The cured gaskets will permanently adhere to the interior of the shell.

According to another technique the proper amount of gasket material can be deposited in the corner portion and then it can be correctly shaped by a forming die which may also be heated so as to simultaneously shape and cure the gasket material.

The present invention is not particularly concerned with either the details of the gasket composition or the particular technique used in forming it into the gaskets 10. Rather, any suitable rubber-like resilient gasket material having the proper physical and chemical properties may be used, and any suitable manufacturing techniques may be employed.

The sealing finish of the glass jar 5 comprises a top edge portion 30 which merges with a beveled or tapered side seal portion 31. The relative relationship of the gasket 10, and the glass finish when the closure cap 6 is in fully sealed position are shown in FIG. 7. The closure caps 6 are applied to the filled glass jars 5 and turned down to fully sealed position thereon in known manner using known high speed capping equipment. Generally, this combined capping and sealing operation begins with applying the caps loosely onto the mouths of the jars

passing through an atmosphere of steam, and then turning the caps down lightly to position with the lugs 12 engaging underneath the glass lugs 13. Then while the jars are restrained from turning, the caps 6 are turned down to their full down and sealing position bringing about the relationship of the gasket and sealing finish shown in FIG. 7. The head space in each of the jars is filled with steam during the capping operation so that when this trapped steam condenses after capping, a vacuum is created within the head space which enhances the hermetic seal between the gasket 10 and the glass finish.

Referring to FIG. 7 it will be seen that the top edge of the sealing finish of the glass container has upwardly compressed the gasket material in the cushion area 23 with the result that an inner part of the gasket material is bulged inwardly as indicated at 32 in FIG. 7. However, the bulged portion 32 is under compression so that there is no tendency to lift or loosen the seal formed between the gasket and the interior of the shell in the vicinity of the lower end of the channel wall 16 where the gasket edge terminates at 27. At the same time the tapered portion 24 of the gasket is upwardly ironed or drawn out so as to completely blanket the inclined side sealing area 31 of the glass finish and extend downwardly there beyond to the vertical portion of the glass exterior indicated at 33. It will be seen that the gasket material is materially thinned out where it is caught between the glass finish 31 and the opposing skirt portion area 20 of the cap shell. As a matter of fact the cap shell in this area is placed under hoop tension as a result of sealing. This condition is indicated in FIG. 7 wherein the original contour of the unapplied cap shell is shown in broken lines 34 while the distended applied condition is shown in full lines as indicated at 35. This hoop tension in the shell places the adjacent gasket material under compression and brings about a very high degree of sealing action in this region.

As indicated above, there are three main sealing areas provided by the gasket 10 in combination with the cap shell and the sealing finish on the rim of the container. The first seal is formed at the feather edge 26. Since this seal is located at a relatively remote distance from the portions of the gasket which are engaged with the glass finish, and because of the thinness of the feather edge portion and the inability thereof to transmit compression forces, this feather edge seal at 26 is fully protected and easily maintained so that no part of the atmosphere has an opportunity to gain entrance between the gasket 10 and the cap shell portion 3.

The second portion of the seal is in the area where the thinned out, tapered skirt portion 24 of the gasket is maintained under radial compression between the distended portion 35 of the cap shell and the unyielding opposing tapered finish 31. The leakage rate in this portion of the seal is reduced to a minimum since it will be seen that for any part of the atmosphere to pass this seal it will have to travel through the gasket, not cross-wise or transversely in the narrow direction but lengthwise and parallel to the drawn out portion. Hence, for practical purposes there is no leakage to speak of through this portion of the seal.

Thirdly, there is the cushion seal formed between the upper edge portion 30 of the glass finish and the thick portion 23 of the gasket. This is the portion of the gasket which bears the greatest load when the package undergoes retorting with high overriding or differential pressures. Heretofore, with other caps having thinner cushions of gasket material in this region, it was not uncommon for the high overriding pressures to result in the gasket being completely penetrated so that the glass finish in effect severed the cushion and reached the metal shell itself. In the gasket 10 the amount of material disposed in the channel 15 is sufficient so as to prevent such penetration from occurring.

By reason of the padding and cushioning action provided by the thick portion 23 of the gasket, the sealed package is able to withstand substantial and repeated impacts and shocks received in generally axial direction. Since the tapered, elongated portion 24 of the gasket is maintained under compression in confined relationship between the glass finish and the cap shell, it is able to withstand substantial impacts from a generally lateral direction. The net result is that a package sealed with the closure cap 6 is more resistant to shocks and impacts without the hermetic seal being broken than caps of this type heretofore provided.

The closure cap 6 described above in detail in connection with the accompanying drawings represents the presently preferred embodiment of my invention. However, certain changes may be made in it. For example, the cap shell on the lower portion of the skirt could be provided with thread formations rather than the lugs 12 so as to be a screw cap for cooperation with exterior threads on the glass finish. The exterior diameter of the bottom or outermost skirt portion 22 may be reduced somewhat, and minor variations may be made in the contour of the upper stepped portion of the shell. Minor variations may be made in proportions.

Since the above and certain other minor changes may be made without departing from the spirit and scope of the invention, the foregoing description is intended to be interpreted as illustrative and not in a limiting sense.

What is claimed as new is:

1. In a closure cap of the top and side seal type for use in establishing and maintaining a hermetic seal on a glass container of the type in which the upper edge of the rim together with a portion of the side surface thereof constitute the hermetic sealing finish, and said cap comprising a generally cup-shaped shell having a top panel portion with the margin having a down-turned channel formation to register with said upper edge and having a stepped skirt portion with the upper inner step thereof integrally joining the outer wall of said channel formation as a continuation thereof and providing a downwardly and outwardly tapered side portion the bottom of which directly joins an outwardly flared shoulder portion, the improvement comprising an annular sealing gasket located generally within the corner of said shell having its upper and inner edge located on the underside of said top panel portion adjacent the bottom of the inner side wall of said channel formation with its lower and outer edge terminating in a feather edge on the under-side of said outwardly flared shoulder portion, with said gasket filling said channel formation and having a downwardly and outwardly tapered portion which rapidly diminishes in cross-section below said channel formation and follows said tapered side portion and said outwardly flared shoulder portion and extends to said feather edge, said downwardly and outwardly tapered portion being at least several times longer than the thickness of said channel filling portion; said channel filling portion of said gasket sealingly engaging said upper edge of the sealing finish of said container when said closure cap is hermetically sealed thereon with said tapered portion of said gasket being at least partially thinned out by compressed sealing engagement with said side portion of said sealing finish, and said feather edge lying substantially outwardly of said sealing finish.

2. In a closure cap of the combination top and side seal type for use in establishing and maintaining a hermetic seal on a glass container of the type in which the top edge of the rim together with a contiguous downwardly tapered side surface portion having a height approximately equal to the width of said top edge constitute the hermetic sealing finish, and said cap comprising a generally cup-shaped shell having a top panel portion with the margin thereof having a down-turned channel formation to register with said upper edge and having a stepped skirt portion with the upper inner step thereof integrally joining the outer wall of said channel formation as a downwardly

and outwardly tapered continuation portion the lower end of which directly joins an outwardly and downwardly flared shoulder portion of said skirt which connects with the lower outer step of the skirt which carries inwardly projecting formations for retaining the cap on a container, the improvement which comprises an annular sealing gasket located generally within the corner of said shell having its upper and inner edge located on the underside of said top panel portion adjacent the bottom of the inner side wall of said channel formation and its lower and outer edge terminating in a feather edge on the underside of said shoulder portion, said gasket having an upper cushion portion which fills said channel formation and a downwardly and outwardly tapered portion which rapidly diminishes in cross-section below said channel formation and follows said tapered continuation portion of the shell skirt and connects with said feather edge said downwardly and outwardly tapered portion being at least several times longer than the thickness of said channel filling portion, the inner contour of said gasket when uncompressed being generally arcuate from its upper inner edge to the lower end of said downwardly and outwardly tapered portion thereof, said channel filling portion of said gasket sealingly engaging said top edge of the container rim when said closure cap is hermetically sealed thereon with said tapered portion of said gasket being at least partially thinned out and radially compressed into sealing engagement with said tapered side surface of the sealing finish, and said feather edge portion being disposed substantially outwardly of any portion of said sealing finish, said radial compression on said tapered portion of said gasket being provided by outward flexing of said downwardly and outwardly tapered continuation portion of said skirt.

3. The improvement called for in claim 2 wherein said gasket is formed of a cured plastisol.

4. The improvement called for in claim 2 wherein the inner contour of said gasket when uncompressed is generally S-shaped starting at said upper and inner edge and ending at said feather edge.

5. A sealed package comprising a glass container having a hermetic sealing finish provided in part by the top edge of the rim and in part by a contiguous downwardly tapered side surface and having protruding cap-retaining means below said finish and a closure cap in hermetically sealed relationship on the top of said container, said cap comprising a generally cup-shaped shell having a top panel portion with the margin thereof having a down-turned channel formation in registry with said top edge of said sealing finish and having a stepped skirt portion with the upper inner step thereof integrally joining the outer wall of said channel formation as a downwardly and outwardly tapered continuation portion which telescopes over said tapered side surface of said sealing finish with the lower end thereof directly joining an outwardly and downwardly flared shoulder portion of said skirt which in turn directly joins a lower outer step portion of the skirt which has inwardly protruding cap-retaining means in engagement with said cap-retaining means on said finish, and an annular sealing gasket located generally within the corner of said shell having its upper inner edge located on the underside of said top panel portion adjacent the bottom of the inner side wall of said channel formation and its lower and outer edge terminating in a feather edge on the underside of said shoulder portion, said gasket in its compressed sealing condition being generally ladle-shaped in cross-section having an upper cushion portion corresponding to a ladle bowl and filling said channel formation and having a downwardly and outwardly tapered portion corresponding to a ladle handle which follows said tapered side portion and said outwardly flared shoulder portion of said shell skirt and extends to said feathered edge, said upper cushion portion sealingly engaging said top edge of said finish and that section of the length of said tapered portion of the gasket which lies between said tapered side surface of the sealing finish and said

tapered side portion of said skirt being radially thinned out and compressed into sealing engagement with said tapered side surface by hoop tension provided by outward flexing of said downwardly and outwardly tapered continuation portion of said skirt, and said feather edge portion being disposed substantially outwardly of any portion of said sealing finish.
